Letters Patent No. 99,491, dated February 1, 1870.

BASE-BURNING PARLOR COOK-STOVE

The Schedule referred to in these Letters Patent and making part of the same.

To all whom it may concern:

Be it known that I, DAVID L. STILES, of the city of Rochester, county of Monroe, and State of New York, have invented a certain new and useful Improvement in Parlor Cook-Stove; and I do hereby declare that the following is a full and exact description of the same, reference being had to the accompanying drawing, making part of this specification, in which—

Figure 1 is a perspective view of my improved stove.

Figure 2, a vertical section in plane of line *x x*.

Figure 3, a horizontal section in plane of line *y y*.

Like letters of reference indicate corresponding parts in all the figures.

Nature of Invention.

This stove is of that class known as base-burning or self-feeding.

The invention consists—

First, in forming an oven in the bottom part of the stove, under the fire-pot, by the use of an adjustable diaphragm or screen, which closes or shuts to catch the ashes; and

Second, in the construction of the upper portion of the body of the stove, to allow boiler-holes to be formed at the sides.

General Description.

In the drawings—

A indicates the main body of the stove, and B the upper portion of the same, which surrounds the magazine P; said main body, and its upper portion, being, preferably, of triangular form, with the sides of the upper portion hollowed out or concave, to allow the use of the boiler-holes, as hereinafter described.

The interior of the body has a fire-pot, K, of any desired construction; but I prefer that patented to me, March 17, 1868, in which a series of hollow staves, bound together, is used. There is nothing peculiar about this portion of my present invention, except that I use a series of draught-holes, *a a a*, above the oven, presently to be described, and opening into the top of the fire-pot, through the annular air-space of which the air circulates, passing down, and entering the fire at the base of the pot in a highly heated state, where it readily supports the combustion.

This leading of the draught-openings into the hollow space of the fire-pot, at the top of the same, and above the oven-space, I claim to be a novel feature.

Beneath the fire-pot is a large open space, C, which ordinarily serves as an ash-pit. But when cooking is to be done, it serves as an oven, by interposing a diaphragm or screen, D D, at the top, between it and the fire-pot; which diaphragm or screen serves, in that case, to catch the ashes, and prevent their falling into the oven.

An open passage or space, b, is left above the diaphragm, thus forming a communication between the oven and the fire-chamber, so that heat can come down readily, and the engendered gases of the oven pass off through the draught-flues.

Any desired construction of the diaphragm may be used; but that shown in the drawing, which consists of double flaps hinged at the sides, and held by a suitable catch-arrangement, is a convenient one. In this case, the flaps can turn down against the sides of the oven, out of the way, when not in use, as indicated in dotted lines, fig. 2.

Beneath the oven is a hot-air space, E, which communicates with the fire-chamber by vertical flues, c c, in the two front corners of the stove, and with the exit-pipe by a similar flue, e', in the rear. By this arrangement, a downward-flue stove is produced, which always keeps the base warm, and the desired heat is produced under the oven, and at its sides and rear, to equalize the heat from the fire-chamber above it, by which means a gentle and uniform temperature is sustained on all sides, which is necessary in cooking.

I am aware that ovens have frequently been applied to parlor-stoves, but generally at the top and back side, where they do not receive the desired heat; and where they are unsightly, and unhandy in use. Ovens of that kind could not be applied to base-burning or self-feeding stoves, since the magazine filled with coal would interpose a barrier, which would obstruct the heat. By my invention, I not only adapt an oven to a self-feeder, but also locate it at the bottom, the point where the greatest heat comes, and I surround the oven by hot-air flues and spaces, which produce an equality of temperature at all sides. In such an arrangement there is no external projection or sign of an oven, but simply the regular outline of a parlor heating-stove.

This result is secured simply by the use of the diaphragm D D, which cuts off the ashes from above, but still allows a free communication with the fire-chamber by space b.

On the top of the main body of the stove are formed boiler-holes, G G, situated directly over the flues c c, which have the inner plate running sufficiently high to carry the heat up close under the holes before it escapes down the flues. These holes, preferably, have mica covers, d d, as clearly shown in fig. 1, by which, when the holes are not in use, a good light is obtained from the fire; but any desired covers may be used.

The triangular construction of both the main body and upper portion of the same, with the concave sides around the magazine, allows sufficient space for the use of these boiler-holes on each side of the magazine, which is not the case in other self-feeding stoves, with which I am acquainted. By this means, boiling as

well as baking, can be effectually done in this stove, as the boiling, as well as the baking, comes in close proximity to the fire-chamber, which cannot be done in other self-feeding stoves.

What I claim as my invention, and desire to secure by Letters Patent, is—

1. The arrangement, in a parlor-stove, of the adjustable diaphragm D D, when combined with the open space C, in such a manner as to adapt said space to use, either as an oven or ash-chamber, as herein described.

2. In a base-burning parlor-stove, the construction of the body A, and its upper portion B, surrounding the magazine, in such a manner as to leave space out-

side the said upper portion B for the boiler-holes G G, the whole arranged as described, and for the purpose specified.

3. In combination with the fire-pot K, and the oven-space C, the arrangement of the series of draught-holes a a, situated above said oven-space, and opening into the top of the fire-pot, as described.

In witness whereof, I have hereunto signed my name, in the presence of two subscribing witnesses.

D. L. STILES.
